UNITED STATES PATENT OFFICE.

MICHAEL SNEE, OF LOS ANGELES, CALIFORNIA.

BALL-BEARING RAIL.

Application filed April 27, 1927. Serial No. 186,840.

This invention relates to ball bearing rails, and particularly to a type of rail such as is used in railroad tracks. The invention has for an object the provision of a rail which is so constituted and constructed as to reduce the friction between said rails and the rolling stock, particularly at curves in said rails.

Another object is the provision of a rail which permits the rolling stock to run quietly, and likewise lessens the tendency of the wheels of the rolling stock to leave the rails.

The inventor has found by calculation that on ordinary railways, equipped with ordinary sized gauge of rails and ordinary sized car wheels, that the resistance on a 10° curve is approximately forty per cent of the gross weight of the train, and for a 5° curve twenty per cent. It is with the idea of overcoming this resistance to an appreciable degree that the present invention is directed.

Other objects include simplicity of manufacture, general economies in use and practice, ease of maintenance, and great durability and efficiency in actual use and service.

With the above and other objects in view, the invention consists in the novel and useful provision, formation, construction, association and interrelation of parts, members and features, all as shown in certain embodiments in the accompanying drawing, described generally, and more particularly pointed out in the claims.

In the drawing:

Fig. 1 is an end elevation of a car wheel resting upon a rail, the said rail incorporating the invention;

Fig. 2 is a fragmentary side elevation, partly in section, illustrating the construction of the improved rail;

Fig. 3 is a plan view of the showing of Fig. 2;

Fig. 4 is a plan view of a curved rail; and

Fig. 5 is a plan view of certain means used in practising the invention.

Corresponding parts in all the figures are designated by the same reference characters.

Referring now with particularity to the drawing, the improved device is designated as an entirety by A, the same including a rail *a* and anti-friction means *b*, both of which elements may be used in practising an embodiment of the invention. The rail is conventional in form, including the usual head 1, web 2, and flange 3. The head of the rail, and along a side thereof, is formed with

a longitudinal curved groove 4. Adapted to be placed within the said groove is the anti-friction means *b*, which in the present instance constitutes one or more roller bearings 5. The curved groove 4 is constructed so as to in part encircle the roller bearings 5, and yet permit said roller bearings to have a portion of the periphery thereof projected outwardly from the side face 6 of the head 1, as shown at 7. Any convenient method may be utilized in the forming of the groove 4, such as by boring or casting. The distance of projection of the roller members beyond the face of the rail will depend upon the use and service intended. Referring to Fig. 1, it will be seen that the roller bearings 5 are adapted to contact with the face 8 of the flange 9 of the wheel *c*, and that the tread 10 of said wheel rests upon the top surface of the head 1 of the rail. Thus as the wheel revolves upon the rail, the bearing members 5 will contact with the flange 9 and tend to be turned.

In Fig. 4 I have shown a curve in the rail, in which the bearing members 5 will reduce the frictional engagement that would ordinarily occur when the flange of the wheel contacts with the side of the rail head. It would be obvious that smoother running and less noise would result, and the different bearing members could be lubricated in the same manner that rails are now oiled at curved portions. In Fig. 3 a straight length of rail is shown with the bearing members, and such construction tends to save wear and tear on the heads of the rails, and likewise the flange of the wheels, due to jolting motions caused by side winds against the rolling stock, or unevenness of the tracks or roadbed. Likewise, vibration is to an extent overcome in the rolling stock. Less friction between the wheels and the rails will likewise result in a saving in power, with the consequence that running time is lessened between two points, and the resultant expense of the haul would therefore be likewise lessened.

In order to overcome back lash, I have provided some type of resilient means, such as coil springs 11, which coil springs are adjacent the ends of each length of rail, and engage the roller members. These coil springs tend to maintain the different roller members in engagement, but it is evident that contact of the flange of the wheel with said roller members will tend to move them

backward, and the coil springs 11 tend to overcome this backward movement by again moving the rollers forward. This would be the case also if the train were backing. The means as shown at 12 for closing the ends of the groove 4 may comprise any type of plug, such as a screw plug. In order that the flange of the wheel should not directly strike the end rollers, the portion as shown at 13 which constitutes an ungrooved part of said rail, will be flush with the front of the rollers in order that no depression will occur at these zones. Consequently, the rollers will not be subjected to sudden shock when the flange of the wheel of the rolling stock contacts therewith. Furthermore, the coil springs permit the rollers to rotate, due to the give or the resilient mounting afforded thereby for the said rollers within the groove. 20 The groove is preferably of greater diameter than the diameter of the rollers, so that the rollers may be easily inserted within the groove, and likewise so that the rollers will readily rotate. The rollers may be 25 formed from various materials, such as toughened steel.

It is obvious that various changes and modifications and variations may be made

in practising the invention in departure from the particular showing of the drawing, without departing from the true spirit thereof. 30

Having thus disclosed my invention, I claim and desire to secure by Letters Patent:

1. In a rail, roller members within said rail, and projecting outwardly from a surface of said rail, and resilient means for maintaining said roller members in contact. 35
2. In a rail, anti-friction means projecting in part beyond a surface of said rail, and means permitting said anti-friction means to move in one direction under applied stress, and to restore said anti-friction means to a selected position when said applied stress is relieved. 40
3. In a rail having the usual head, said head being formed with a longitudinal groove, roller members within said groove and projecting in part through said groove and beyond a surface of the head, said rail adjacent an end of the said groove being 45 substantially flush with the front of the roller members. 50

In testimony whereof, I have signed my name to this specification.

MICHAEL SNEE.
